UNITED STATES PATENT OFFICE

WILLIAM HENRY GOETTSCH, OF HOLSTEIN, IOWA

BROODER ALARM

Application filed April 4, 1929. Serial No. 352,439.

The present invention relates to an alarm for brooders and has for its prime object to provide a thermostatic controlled circuit closer whereby an alarm may be energized when the temperature becomes too low or too high in the brooder.

Another very important object of the invention resides in the provision of an improvement of this nature which is exceedingly simple in its construction, inexpensive to manufacture, strong and durable, thoroughly efficient and reliable in its use and operation and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a brooder showing a portion of the hood broken away so as to illustrate the position of my improved structure,

Figure 2 is a top plan view thereof,

Figure 3 is a top plan view of the box with the cover removed,

Figure 4 is a longitudinal vertical section therethrough;

Figure 5 is a vertical transverse section therethrough.

Figure 6 is an enlarged detail horizontal section showing the manner in which one end of the board is mounted in one end wall of the box,

Figure 7 is a perspective view of the board with the curved bracket thereon, and

Figure 8 is a perspective view of the thermostat wafer and the switch arm attached thereto.

Referring to the drawings in detail it will be seen that the numeral 5 denotes the hood of a brooder with a heating element such as a lamp 6 mounted therein. A box B is mounted on the lamp as illustrated in Figures 1 and 2 and comprises a bottom 7, end walls 8 and side walls 9 and 10. The end walls 8 are provided in their central upper portions with transversely extending elongated

interior depressions 11 for receiving the ends of a board 12 which may be sprung in place and thus supported in a horizontal position in the upper portion of the box. Oblong opening 14 is provided in the wall 9 opposite the board 12 and has a screen 15 therein. A cover 16 is provided for the box and is preferably hingedly mounted or engaged as at 17 with the wall 9 and has a locking means 18 associated with the wall 10.

The wall 9 is disposed adjacent the lamp so that the heat of the lamp may readily pass through the opening 14.

A thermostat wafer 20 is anchored as at 21 on the board 12 and has a rod 22 extending therefrom in substantial parallelism with the board 12 and thereover. A curved bracket member 24 has one end fixed to the board by means of contact bolts 25 so as to rise from the board and the upper end thereof has a screw 27 adjustably mounted therein.

The terminal of the arm 22 is disposed between the contact screws 27 and the contact bolts 25. The battery 28 is located in the bottom of the box B and wire 29 from one terminal is connected as at 30 with the intermediate portion of the arm 22.

A wire 30 leads from the other terminal of the battery to an alarm such as an electric bell 31 and a wire 32 leads from the electric bell to the bolt 25.

From the above detailed description it will be seen that when the temperature rises to a certain degree in the brooder the wafer 20 will be expanded so as to cause the arm 22 to engage contact screws 24 thereby closing the alarm circuit. On the other hand should the temperature fall in the brooder too low then the wafer will contract and allow the arm 22 to engage the contact bolt 25 thereby closing the alarm circuit.

Obviously the temperature at which the alarm may be sounded either in raising or lowering the arm 22 may be controlled by adjusting the bolt 25 and the screw 27.

It is thought that the construction, operation, utility and advantages of this invention will now be quite apparent to those skilled in this art without a more detailed description thereof.

The present embodiment of the invention, however, has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what

15 I claim as new is:

In an alarm of the class described, a closed casing having depressions in its opposite end walls provided with resilient sides, said casing having a heat admitting opening in one of its side walls, a thermostatic switch mounted in and completely housed by said casing including a supporting member having snap engagement with said depressions, a thermo-responsive wafer secured to said supporting member and arranged adjacent said heat admitting opening, an arm fixed at one end to said wafer, a curved substantially U-shaped bracket, a contact bolt adjustable thru said supporting member and the lower end of said bracket and securing said bracket to said supporting member, a contact bolt adjustable thru the upper end of said bracket, said contact bolts being arranged in the path of movement of the free end of said arm, and an electrical alarm circuit including said arm and contact bolts.

In testimony whereof I affix my signature.

WILLIAM HENRY GOETTSCH.
